UNITED STATES PATENT OFFICE.

JOHN KENLON, OF NEW YORK, N. Y.

METHOD AND APPARATUS FOR REMOVING SNOW.

1,150,946.

Specification of Letters Patent. Patented Aug. 24, 1915.

Application filed March 27, 1914. Serial No. 827,665.

To all whom it may concern:

Be it known that I, JOHN KENLON, a citizen of the United States, and a resident of the borough of Manhattan, in the city, 5 county, and State of New York; have invented or discovered certain new and useful Improvements in Methods and Apparatus for Removing Snow, of which the following is a specification.

10 My invention relates to a method and apparatus for removing snow, and particularly to a method and apparatus for removing snow which may utilize existent sewer and water systems, although it is not limited 15 necessarily in its utility by the presence of such systems.

The removal and clearing away of snow expeditiously and cheaply is a serious problem in many places, particularly in thickly 20 settled communities and where street traffic is heavy.

In the prevailing method of snow removal, the snow is loaded into carts and conveyed to the nearest available dumping 25 ground for disposition. The time and the expense of such removal are largely, if not almost entirely, controlled by the distance of the dumping ground from the place to be cleared. By my method and apparatus 30 dumping grounds may be provided in any desired number and at convenient intervals, and each apparatus will dispose of snow conveyed to it effectively and completely at a minimum of time and cost.

35 Referring to the drawings accompanying and forming a part of this specification, wherein I have illustrated one embodiment of an apparatus adapted to carry out my method: Figure 1 is a plan view of an apparatus adapted to carry out my method; and Fig. 2 is a vertical section thereof.

Similar reference characters refer to similar parts throughout the drawings.

Reference character 1 indicates a suitable 45 conduit, or established sewer system if one is available; reference character 2 an opening or chute or a plurality of such openings or chutes; and reference character 3 a water conveyer. The chutes either should be at a 50 sufficient incline to cause the snow to fall to conduit 1, or they should be provided with jets of water or with other suitable means to force the snow to the conduit. It is preferable, but not necessary that the 55 chutes enter conduit 1 at an angle, thereby aiding the emulsifying action to be referred

to later. An arrangement of four chutes as illustrated in Fig. 1 forms an advantageous arrangement. Water conveyer 3 may consist of any device to convey water to the 60 conduit, such as a pipe 4 supported by brackets 5, as illustrated in Fig. 2.

A source of water supply is indicated at 6; which may be established fire hydrants if available, connected to water conveyer 3 65 in any desired manner as by hose 7. The end of the water conveyer extends into or near the top of the conduit a sufficient extent to direct jets or a stream or streams of water on the entering snow and on the snow in the 70 sewer or conduit 1, or to employ any other desired means capable of emulsifying the same. I have found that revolving or so-called distributing nozzles 8, such as are used by fire departments, emulsify the snow 75 rapidly and effectively.

In order to protect the sides of the conduit from the wearing effect of the emulsifying stream or streams, it is desirable to provide metal plates or other protecting 80 means as indicated at 9, which protection may be extended also to chutes 2, as indicated at 10.

11 indicates one of many means which may be employed to convey the snow along 85 the chutes to the conduit, and 12 indicates a water conveyer incorporated as part of a chute or merely placed therein temporarily during the carrying out of my method. This construction contemplates also a plurality of such water conveyers disposed at proper angles to emulsify the entering snow. The members 11, 12, may be entirely omitted if desired.

When my method is used in connection 95 with a high pressure fire department system, it is advisable to provide an automatic valve 13 which may be of the type described in my Patent No. 946,228, January 11, 1910, and which is adapted to maintain a constant 100 pressure of water in the water conveyer and its constituent parts. If such a valve were not provided a fire in the vicinity of the apparatus would result in an increased water pressure in the apparatus with disastrous 105 results.

A velocity jet 14 in the conduit results in greater efficiency, obviating all danger of stoppage in the conduit. I have found that such a jet located about twenty (20) feet 110 up-stream from the emulsifying means gives excellent results, but, if used, it may be lo-

cated wherever greatest efficiency will result, depending upon velocity of the jet, size of conduit, and rate and amount of flow in the conduit.

5. The operation of the apparatus illustrated to carry out my method is believed to be apparent from the foregoing description. The snow 15 is shoveled or conveyed to chutes 2 through which it reaches conduit 1. As the 10 snow enters the conduit it is emulsified by the stream or streams of water provided for that purpose and is carried away by the conduit without possibility of clogging or stoppage. The saving in time and in expense of 15 snow removal by this method is obvious.

While I have described one embodiment of an apparatus adapted to utilize my method, I am aware that both the apparatus and the method may be modified without 20 departing from the spirit of my invention or from the scope of my claims.

What I claim is:

1. A method of snow removal consisting of conveying snow to a conduit and emulsifying the snow by revolving streams of water so that it will be carried off by said conduit.

2. A method of snow removal consisting of delivering snow to a conduit through a 30 plurality of chutes entering the conduit at substantially the same point and emulsifying the snow so delivered so that it will be carried off by said conduit.

3. A method of snow removal consisting of conveying snow by a jet of water to a conduit and emulsifying the snow so that it will be carried off by said conduit, and aiding the carrying off of said snow by another jet of water.

4. A method of snow removal consisting of conveying snow to a conduit and emulsifying the snow so that it will be carried off by said conduit, and aiding the carrying off of said snow by a jet of water, applied upstream from the emulsifying action.

5. In a snow removing apparatus the combination of a conduit adapted to receive snow and means comprising revolving streams of water to emulsify the snow so that it will be carried off by said conduit.

6. In a snow removing apparatus, the combination of a conduit, a chute adapted to convey snow to said conduit, and means within said conduit to emulsify said snow so that it will be carried along said conduit.

7. In a snow removing apparatus, the combination of a conduit, a chute adapted to convey snow to said conduit, and means within said conduit to emulsify said snow as it enters said conduit, so that it will be carried along said conduit.

8. In a snow removing apparatus, the combination of a conduit, a chute adapted to convey snow to said conduit, and means within said conduit to emulsify said snow in

said conduit, so that it will be carried along said conduit.

9. In a snow removing apparatus, the combination of a conduit, a chute adapted to convey snow thereto, and means to emulsify the snow comprising streams of water emanating from within said conduit so that the snow will be carried off by said conduit.

10. In a snow removing apparatus, the combination of a conduit, a chute adapted to convey snow thereto, and means to emulsify the snow comprising revolving streams of water so that the snow will be carried off by said conduit.

11. In a snow removing apparatus, the combination of a conduit, chutes entering said conduit at an angle and adapted to convey snow thereto, and means located where the chutes enter said conduit to emulsify the snow so that the snow will be carried off by said conduit.

12. In a snow removing apparatus, the combination of a conduit, a chute adapted to convey snow thereto, means to emulsify the snow comprising streams of water emanating from within said conduit so that the snow will be carried off by said conduit, and means to protect said conduit from the wearing action of said streams.

13. In a snow removing apparatus, the combination of a conduit, a chute adapted to convey snow thereto, means to emulsify the snow comprising streams of water emanating from within said conduit so that the snow will be carried off by said conduit, and means to protect said conduit and said chutes from the wearing action of said streams.

14. In a snow removing apparatus, the combination of a sewer system, a water system, chutes entering said sewer system at an angle to said sewer, and means connecting said water system to said sewer system comprising a device located within said sewer to emulsify snow entering said sewer from said chutes.

15. In a snow removing apparatus, the combination of a conduit, a chute adapted to convey snow thereto, means to emulsify the snow comprising streams of water emanating from within said conduit so that the snow will be carried off by said conduit, and a device to maintain the said streams of water at constant pressure.

16. In a snow removing apparatus, the combination of a conduit, a chute adapted to convey snow to said conduit, means located within said conduit to emulsify said snow so that it will be carried along said conduit, and a device to convey a jet of water into said conduit to aid the flow in said conduit.

17. In a snow removing apparatus, the combination of a conduit, a chute adapted to convey snow to said conduit, means to emulsify said snow so that it will be carried along

said conduit, and a device to convey a jet of water into said conduit up-stream from said emulsifying means to aid the flow in said conduit.

5 18. In a snow removing apparatus, the combination of a conduit, a plurality of inclined chutes arranged to deliver snow to said conduit at substantially the same point, and means for emulsifying the snow so delivered, for the purpose described.

10 19. In a snow removing apparatus, the combination of a conduit, a plurality of inclined chutes arranged to deliver snow to said conduit at substantially the same point; and means located within the conduit for

emulsifying the snow so delivered, for the purpose described.

20. In a snow removing apparatus, the combination of a conduit, a plurality of inclined chutes arranged to deliver snow to said conduit at substantially the same point; and means located within the conduit and adapted to emit streams of water for emulsifying the snow so delivered, for the purpose described.

JOHN KENLON.
